UNITED STATES PATENT OFFICE.

WILHELM SCHRAMM AND FREDERICK BECKER, OF NEW YORK, N. Y.

HEATING APPARATUS.

No. 876,495.

Specification of Letters Patent.

Patented Jan. 14, 1908.

Application filed May 3, 1907. Serial No. 371,756.

To all whom it may concern:

Be it known that we, WILHELM SCHRAMM and FREDERICK BECKER, both subjects of the German Emperor, and residents of New 5 York, county and State of New York, have invented certain new and useful Improvements in Heating Apparatus, of which the following is a specification.

The present invention pertains to heating 10 apparatuses and particularly to such that are designed for use in smoke houses for smoking meats, sausages and the like, and has for its object to provide a construction by means of which the heat of an ordinary 15 gas burner can be greatly increased to be available for above purposes.

Our invention is illustrated in the accompanying drawing in which similar reference letters denote corresponding parts and in 20 which

Figure 1 is a vertical section through our apparatus; Fig. 2 a plan view thereof, the reflector being removed and Fig. 3 is a cross section through line 3—3 of Fig. 1.

With reference to the drawing, *a* denotes the burner pipe which is adapted to be connected with the gas supply pipe and which may be formed as a Bunsen burner. The upper end of this burner pipe terminates into 30 and is secured to an open topped metal casing *b* which at its lower portion and in its bottom is provided with a number of air holes *c*. Attached to the top of said casing, is a support *d* carrying a vertically and centrally extending rod *e* that projects into the casing *b* and is capable of being vertically adjusted. Rigidly secured to the bottom of 35 said rod *e* and surrounding the latter is a hollow conical body *f* the apex of which is directed towards the mouth of the gas burner. This conical body *f* is open at its top and is provided with a plurality of perforations *g* on its circumference. Secured to the circumference of the conical body is a 40 spiral flange *h* preferably made of a metal that is a good conveyer of heat, as for instance, sheet copper or the like. This spiral rib is curved to form a trough shaped concave surface directed towards the bottom of 45 the casing *b*. The upper end of the rod *e* is provided with screw thread and carries a nut *i*, by the rotation of which the rod can be adjusted in vertical direction whereby 50 the conical body *f* is brought nearer to and farther from the mouth of the gas burner. Secured to the free end of the rod *e* and ex-

tending over the casing *b* is a concaved heat reflector *j*. The lower end of the rod *e* may be guided in vertical direction by a cross wire *k* attached thereto and having its downwardly bent ends *l*, *l* guided in brackets *m*, *m*.

The mode of operation of this apparatus, is as follows: The flame at the mouth of the gas burner acts against the lower end of the spiral flange *h* which as stated, being a good conveyer of heat, gradually conveys the heat to the upper end of the conical body, rendering the same red hot. At the upper end, the heat is reflected by the reflector *j*. The flame also passes through the perforations *g* into the hollow space of the conical body and heats the latter also from the inside, which prevents the heater from being cooled down by the cold air entering from the top of the heater.

Having thus described the nature of our invention, what we claim and desire to secure by Letters Patent is:

1. A heating apparatus comprising a burner pipe, an open topped casing secured to the mouth of the latter, an adjustable open topped conical body projecting with its apex downwards into the casing towards the mouth of the burner pipe, said body being hollow and having a spiral flange on its circumference, the said flange being a good conveyer of heat, and a heat reflector above said casing and conical body, substantially as set forth.

2. A heating apparatus comprising a burner pipe, an open topped casing secured to the mouth of the latter, and having air holes at its lower portion and in its bottom, a support secured to the top of the said casing, an adjustable open topped conical body suspended from said support and projecting with its apex downwards towards the mouth of the said casing, said body being hollow and having perforations on its circumference, and a spiral flange which is a good conveyer of heat, and a heat reflector above said casing and conical body, substantially as set forth.

3. A heating apparatus comprising a burner pipe, an open topped casing secured to the mouth of the latter, a support at the end of said casing, a rod adjustably borne in said support and projecting centrally downwards towards the mouth of the said burner pipe, an open topped conical body secured to said rod and surrounding the latter; said conical body being hollow and having per-

forations and a spiral flange on its circumference, the latter being a good conveyer of heat, means for guiding the lower ends of said rod and conical body in vertical direction, and a heat reflector secured to the upper end of the said rod above the casing and the conical body, substantially as set forth.

Signed at New York this 1st day of May, 1907.

WILHELM SCHRAMM.
FREDERICK BECKER.
